UNITED STATES PATENT OFFICE.

EDGAR A. WRIGHT, OF CHICAGO, ILLINOIS, ASSIGNOR TO THE DEERING HARVESTER COMPANY, OF SAME PLACE.

HAY-RAKE.

SPECIFICATION forming part of Letters Patent No. 586,264, dated July 13, 1897.

Application filed June 19, 1895. Serial No. 553,377. (No model.)

To all whom it may concern:

Be it known that I, EDGAR A. WRIGHT, of Chicago, in the county of Cook and State of Illinois, have invented certain new and useful Improvements in Hay-Rakes, of which the following is a clear and full description, reference being had to the accompanying drawings, in which—

Figure 1 is a plan view of a hay-rake in which my invention is exemplified. Fig. 2 is a sectional elevation showing the rake-teeth and their controlling parts in the normal position, Fig. 3 is a similar view showing the rake-teeth and their controlling parts in the discharging position. Fig. 4 is an enlarged sectional elevation. Fig. 5 is a front view of one end of the rake-head and adjacent carrying-wheel and parts. Figs. 6, 7, 8, 9, 10, 11, and 12 are details of construction. Fig. 13 is a plan view of the convertible pole and shafts when in the position to be used as a pole. Figs. 14 and 15 are side elevations showing a manual discharging apparatus applied to the rake. Fig. 16 is a sectional view of the ratchet-wheel D.

My invention refers to that class of hay-rakes which is supported on two carrying-wheels and drawn by animal power and in which the rake-head carrying the rake-teeth is adapted to be rocked upon the axles of the said carrying-wheels as axes in order to discharge the load.

The object of my invention is to provide a rake that is more effective in its operation and more durable and less expensive in construction.

Referring to the drawings, A and A' are the usual carrying-wheels.

B is the rake-head, preferably of angle-steel, and to which the rake-teeth are attached. The rake-head terminates at each end in axle-seats B' and B'', suitably secured thereto, preferably, as shown, by bolts. The stub-axles b' and b'' are secured at b³ and b⁴. As shown in Figs. 5, 6, and 8, the axle-seats are secured to the rake-head by bolts b⁵, two of which are further utilized in securing the axle b'.

The hubs a of the carrying-wheels are fitted with bushings a', the peculiar feature of

which is the means by which the ratchet-wheels D are secured thereto.

Referring to Figs. 11 and 12, will be seen lugs a² on the bushing near its inner end. In the ratchet-wheel D, Fig. 12, is an aperture d, having notches d', corresponding to the lugs or projections a² on the bushing. 55

d² d³ are inclined surfaces upon the face of the wheel D. To secure the said ratchet-wheels to the said bushings, they are slipped 60 thereon from the inner end past the lugs a² and then given a peripheral motion in a direction opposite the direction of wheel travel until they tighten by means of the inclines d², binding between lugs a² and the flanges a³. 65

Axle-seats B' and B'' are provided with shields and supports for an automatic discharging attachment, as shown in Figs. 5 and 6. In Fig. 8 is shown a similar axle-seat B³, adapted to be secured by the same bolts to 70 the rake-head B, to be used when a manual discharge device is used and which does not have a shield for the ratchet-wheel or a support for the trip-rod, which is unnecessary in a hand dump-rake. 75

When rake-head B, carrying the teeth C, is rocked to discharge the load, it rocks upon the stud-axles b' and b'' in the supporting-wheels, when used either as an automatic or a hand dump-rake. When used as an auto- 80

matic dump-machine, the head is thrown into engagement with the wheels in order that it may be rocked to discharge by the mechanism which will now be described. The trip-rod F is rotatably supported in the castings 85 B' and B'' at f' and f'', and its ends F' and F'' are made pawl-shaped, so as to suitably engage the teeth of the ratchet-wheels D. The trip-rod is controlled by a cam G, which is pivoted upon the bracket g, suitably secured 90 to the hound-frame. The cam-lever extends rearwardly from its pivot, which extension has formed therein a curved slot g', and extends forwardly, terminating in a foot-pad g². The rod F is bent in the form of a crank at 95 the point f³, which crank is situated so as to engage the cam-slot g' and radiate from the rod F relatively to the pawls F' and F'', so that the weight of the said lever G acts to hold the pawls at the ends of the rod nor- 100

mally out of engagement with the ratchet-wheels D. The pawls are thrown into engagement with the ratchet-wheels by the operator pressing with his foot upon the pedal 5 g^2 of the lever g, as will be seen by referring to Fig. 9, in which the full lines indicate the tripped position and the dotted lines the normal position of the cam-lever and trip-rod. When tripped as above described, the 10 rake-head is rocked upon the stub-axles as centers by means of the ratchet-wheels and the trip-rod supported and carried in the axle-seats B' and B² until the parts reach the discharging position, (shown in Fig. 3,) when 15 the crank f³ reaches the end of the slot in the cam-lever. A continued stress of parts to rock the rake-head, forcing the pawls out of engagement with the ratchet-wheels, causes the rake-head to drop back to its initial position. 20

To hold the rake in its raking position until a sufficient load has been gathered, a foot-lever H is provided, pivoted in the bracket h, and has a footpad h' attached at its upper end 25 by means of which the operator applies stress to hold the rake in the raking position. A bracket h², suitably secured to the rake-head, serves a double purpose, one to sustain the trip-rod in about the center of its length and 30 another to afford a pivot to which the connecting-rod H' is attached, which connecting-rod connects the foot-lever to the rake-head. The rear end h³ of the said connecting-rod is slotted in order that the rake-head may have 35 a limited movement, or, in other words, to give a limited floating action to the rake as a whole as it travels over uneven ground. The front end h⁴ is preferably provided with a number of adjustment-holes by which the 40 foot-lever and the connecting-rod can be coupled together, so that the positions of the points of the teeth are adjustable to suit the different conditions under which rakes are used. It is desirable that a hand-lever I 45 should be provided in order to move the rake-teeth to their discharging position when the machine is stationary. It is pivoted preferably upon an axle coincident with that of the foot-lever H, and so pivoted as to remain stationary when the rake is moved to discharge 50 its load, unless it is itself the means for discharging the load. This is the preferred construction, because if the lever moved every time the rake was discharged it would be 55 liable to strike the operator. This lever is rendered operative in the manner as above described, preferably by placing it alongside of the foot-lever and in front of the foot-pad at the upper end of the said foot-lever, so 60 that when the said hand-lever is pulled rearwardly by the operator it will strike the said foot-pad and carry the foot-lever with it to discharge the load of the rake.

Pivoted conveniently upon the foot-lever 65 is a latch J, having a toe-pad j at its upper end and a hook or pawl j' at its lower end,

the said hook adapted by the aid of gravity to engage teeth h⁵ upon the bracket h when the rake is moved to its discharging position. A number of teeth may be provided upon the 70 bracket h, so that the latch may engage any one of them, no matter what adjustments are made in the operative lengths of the connecting-rod, as previously described. The purpose of the latch J is to hold the rake-teeth 75 in their discharging position when the machine is being drawn over a road or from field to field. The operator takes his foot off the cam-lever after tripping the trip-rod into engagement with the ratchet-wheels and places 80 it on the pad of the latch J, so that the machine will not be latched in its discharging position under ordinary working conditions. When the parts have returned to their normal position, the operator removes his foot 85 from the latch and places it on the foot-lever to hold the machine when raking.

The teeth C are secured to the rake-head B by clips c, as shown in Figs. 4 and 5. The teeth project forwardly through slots C' in 90 the rake-head, are preferably coiled a number of times to provide elasticity, (preferably twice, as shown,) and extended transversely to form an axis c², the termination of the said axis being bent, as c³. The clip c forms with 95 the rake-head a journal-bearing for the axis c². The bent portion c³ forms a limit to the free play of the rake-tooth in its support, as shown in Fig. 4. It will thus be seen that the rake as a whole has a limited rocking 100 movement in its normal position and also that each rake-tooth has an independent limited movement upon its attachment-clip, and the said movement is limited by the bent portion c³ striking the side of the rake-head. 105

In Figs. 14 and 15 is shown the manual discharge device, which can be applied to the rake in place of the automatic discharge device previously described. N' is an arm bolted to the rake-head B by the same bolts 110 n and n' used to secure the arm h² (previously described) thereto. Link O is pivoted to the said arm N and extends forwardly to a point adjacent to the bracket O', in which the hand-lever P is pivoted. The link O is pivoted to 115 the hand-lever P at p, and its front end o rests upon the ledge o' upon the bracket O', when the teeth are in their raking position. This construction provides a "lock" for the lever, as will be clearly understood by reference to Fig. 14. The bracket O' is secured to the hound-frame by bolts o² and o³, which are also used in securing the bracket h of the self-dump device in the same place. The hound-frame is hinged to the rake-head by 125 hinges secured to both parts by bolts common to both the self and hand dump devices, but the location of the hinge-pivots are preferably different in order that the weight of the operator may assist in dumping the rake. 130

It will be understood that I do not intend to limit my claims to the particular forms of

automatic or manual discharging apparatus herein shown and described, because either may be used in connection with my invention when materially modified.

5 The hound-frame upon which the operator's seat is attached and to which the convertible pole and shafts are attached, as will be hereinafter described, is hinged to the rake-head at k and k' in any convenient manner, and it consists of two pieces, preferably of angle metal, one piece K being bent to form the front sill and the ends k^2 and k^3 , the other piece K' forming the rear sill of the frame. The parts K and K' are preferably secured to each other by means of the hinge-pieces k^4 and k^5 . A draft-bar K^2 is secured to the front and rear sills in the center of their width and projects forwardly to provide means whereby the thills when converted 20 into a pole are attached to the frame and whereby the whiffletree is pivoted to the said frame when the thills are used as thills.

Referring to Fig. 13, it will be seen that when the thills are placed together to form a tongue they are bolted together and lie between the parts k^6 and the draft-iron K^2 . The bolt that secures the whiffletree to the draft-iron is utilized to secure the tongue, and the braces m' and m^2 serve to hold the 30 tongue in place.

The particular means shown in the drawings of attaching the draft-bar to the front sill is a distance-piece k^6 , through which rivets are passed to secure the parts together. This 35 piece extends forwardly in an arm between which and the forward extension of the draft-bar the thills or the whiffletree are attached. The draft-bar K^2 is secured to the rear sill K^3 , when both are of angle metal, preferably 40 by rivets or bolts passing through a distance-piece k^7 , which piece has a rearward extension k^8 , which extension affords means for holding the cleaner L in place. The said cleaner may be considered as any of the well-known kinds and is shown in the drawings 45 as consisting of the gas-pipe l , carried upon the bar k' in brackets l' and l^2 , and rearwardly-projecting fingers l^3 , secured to the said gas-pipe and held in position by the 50 transverse distance-rod l^4 . The cleaner is adapted to rock in the brackets l' and l^2 , and one of the fingers l^3 projects through a slotted hole in the extension k^8 , whereby a limited movement to the cleaner is permitted.

55 M and M' are the thills or shafts bolted to the ends k^2 and k^3 of the hound-frame, preferably by bolts m , and braced to the said frame by braces m' and m^2 . To give the thills the correct position, the ends k^2 and k^3 60 are made to converge forwardly, as shown in Fig. 1. When two horses are used, the thills are converted into a tongue by bolting them to the bar K^2 of the hound-frame, as shown in Fig. 13, and by swinging the braces m' and m^2 upon the bolts that secure them to the 65 said frame and bolting the forward ends of

the said braces to the said thills. When the thills are used as thills, the singletree N is pivoted between the bar K^2 and the casting k^6 . When converted into a pole, it is necessary that the forward ends of the thills should be lower than when the thills are used as thills, owing to the common methods of harnessing horses. The bar K^2 is therefore bent, as shown in Figs. 2 and 3, so as to give 75 the required droop to the pole.

What I claim as my invention, and desire to secure by Letters Patent, is—

1. In a rake, a hound-frame, the front side and end of which consists of a single angle-bar so bent that the said end pieces may converge in a forward direction to contract the space between the thills secured thereto at their forward ends to the extent desired, said angle-bar having its vertical member at the 80 inner side of its ends, and the butts of said thills secured outside of said vertical member and beneath the horizontal angle, substantially as described.

2. A rake hound-frame adapted to receive 90 thills, said frame constructed of angle-iron and consisting of a rear bar, a front piece and end pieces formed by bending the same, said end pieces secured to said rear bar, the butts of the thills bolted within the angles of the 95 said end pieces, and the latter converging in a forward direction to such an extent as to throw the forward extremity of the thills the proper distance apart, substantially as described.

3. In a rake, convertible thills and tongues and hounds constructed in the following manner: a hound-frame formed of a single piece of angle-iron, having end parts converging 105 relative to each other in a forward direction and adapted to receive the butts of the thills substantially as described, secured to the bar K' , and having the intermediate forwardly-projected bar K^2 , secured to the said bent bar and to the bar K^2 , adapted to receive the butts 110 of the thills when placed side by side to form a tongue for the purpose set forth.

4. In a rake, convertible thills and tongue constructed in the following manner: a hound-frame having end parts converging 115 relative to each other in a forward direction and adapted to receive the butts of the thills, substantially as described, and having the intermediate bar and forwardly-projecting bar K^2 adapted also to receive the butts of the thills when placed side by side to form a tongue, the said bars to which the thills are secured when formed into a draft-tongue deflected downwardly relative to the plane of the sides of the hound-frame to which they 125 are secured when used as thills, whereby the tongue so formed is lower at the front end than the parts forming it are when used as thills, substantially as described.

5. In a rake, the combination of the rake- 130 head of angle metal, with a series of teeth projecting through slots in the vertical por-

tion of the said head, and having coils adapted to lie under the said head, said coils terminating in transverse portions which serve as journals, the ends of which are bent, and a 5 series of the clips adapted with the said head to form bearings for the said journals, the angle that the bent portions of the said jour-

nals assume relative to the head determining the amount of free movement of the said teeth in their supports, substantially as described.

EDGAR A. WRIGHT.
